UNITED STATES PATENT OFFICE.

NORMAN E. KLEIN, OF MEDFORD, OREGON.

UNIVERSAL CURVE DEVICE

Application filed October 21, 1927. Serial No. 227,754.

My present invention has to do with devices for facilitating drawing, and more particularly the drawing of curves; and it has for its object the provision of a device for the use of a draftsman, calculated to enable the draftsman to accurately draw curves that approach a straight line as distinguished from sharp bends or arcs of short radii.

My novel device is useful in that it is susceptible of being readily adjusted and adjustably fixed for the guidance of a draftsman in making various curves of the kind indicated.

To the attainment of the foregoing the invention consists in the improvement as hereinafter described and definitely claimed.

In the accompanying drawings forming part of this specification:

Figure 1 is a plan view of the universal curve device constituting the preferred embodiment of my invention.

Figure 2 is a view of the device taken at right angles to Figure 1 and showing some of the parts in section.

Figure 3 is a cross-section on line 3—3 of Figure 1.

Figure 4 is a cross-section on line 4—4 of Figure 1.

Similar numerals of reference designate corresponding parts in all views of the drawings.

Among other elements, my novel device comprises an appropriate frame 1 and a bendable element 2. The element 2 is of steel and possessed of resiliency and is of uniform cross section throughout its length, and consequently the said element 2 is capable of being bent smoothly in proportion to the force applied, and this without the element having small checks or deviations such as occur in corresponding elements of lead or rubber.

In engineering work curves to be plotted of the kind that approach a straight line, as distinguished from sharp bends or arcs of short radii are frequently encountered, and for this class of work my novel instrument characterized by a resilient steel or other appropriate resilient element is particularly adapted.

In addition to the frame 1 and the element 2, my novel device or instrument comprises means at 3 to hold the element 2 against endwise movement. The said means 3 is at one end of the frame 1, and at the other end of the frame is provided means generally des-

ignated by 4 for applying angular bending stresses to the element 2.

Manifestly by the means indicated the element 2 may be given a great number of positions and curves, the means 3 being loosened and the means 4 being adjusted for the desired positioning of the elements 2 and the means 3 being then tightened whereupon the device or instrument may be made ready for use. As will be readily understood various curves may be produced in the manner described. I would have it understood, however, that if a curve such as illustrated by dotted lines in Figure 1 and designated by 5 is desired, the element 2 is first adjusted to the dotted line position in the manner described and then the means 4 is manipulated so as to tend to bend the element 2 by turning of the sleeve 6.

As will be understood from the drawings, the means 3 of my improvement preferably comprises a sleeve 6 journaled in the frame 1 and having diametrically alined apertures 8 on one side of the frame 1 and a flange 9 at the opposite side of said frame 1, a threaded pin 10 disposed in the sleeve 7 and having a diametrical aperture 11 adjusted to be arranged in alinement with the aperture 8 to receive the element 2, and a lock nut 12 mounted on the threaded portion of the pin 10. It will be readily understood that when the nut 12 is loosened, the element 2 may be readily adjusted endwise through the alined apertures 8 and 11, while when the nut 12 is tightened, the element 2 will be forced against the frame 1 and strongly held with respect to said frame 1.

The arm 1^x of the frame 1 is offset at 13 and terminates in a circular enlargement 14. The said enlargement 14 has a circular transverse aperture 15 in which is arranged and adapted to turn about its axis a sleeve 16, said sleeve having adjacent to one end diametrical apertures 17. Fixed with respect to the terminal portion 14 of the frame 1 and arranged at one side thereof is a housing 17^x in which is disposed a worm gear 18 fixed to the sleeve 16 so as to turn therewith. A threaded pin 19 is arranged in the sleeve 16 and has an aperture 20 which when alined with the apertures 17 is adapted to receive the element 2. The means 4 also includes a nut 21 mounted on the pin 19 and adapted to be set against one end of the sleeve 16, a stub housing 22 fixed with respect to and communicating 110

with the interior of the housing 17* and a worm 23 mounted in the said housing and meshed with the worm gear 18 and having a knurled finger piece 24. When the nut 5 last mentioned is loosened, the element 2 may be moved endwise in the alined apertures of the sleeve and pin. When, however, the nut is tightened, the element 2 will be tightly held to said sleeve and pin. It will also be 10 understood that when the worm is turned about its axis, the sleeve and pin will be turned about their common axis, and hence the element 2 will be bent.

Manifestly my novel device or instrument 15 is susceptible of being expeditiously and easily adjusted to impart to the element 2 the curve or configuration desired, and I would also have it understood that my novel device is adapted to be arranged flat on a drawing 20 board and used in convenient manner in the drawing of curves.

Having thus described the invention, what I claim as new and desire to secure by Letters Patent is:—

25 1. A device or instrument for the purpose described, comprising a frame, a resilient bendable element, means on the frame for holding said element at one end thereof against lengthwise movement, and element 30 bending means carried by the frame and including a worm gear, turnable in the direction of the length of said element, means for fastening the bendable element to the worm gear, and disposed to cause arching of

the bendable elements on turning of the worm gear and a worm meshed with said worm gear and adapted to adjust and hold the latter against casual rotation. 35

2. A device or instrument for the purpose described, comprising a frame, a resilient 40 bendable element of uniform cross section throughout its length, adjustable means on the frame for holding said element against lengthwise movement, and element bending means carried by the frame and including a 45 worm gear, means for fastening the bendable element to the worm gear, and a worm meshed with said worm gear and adapted to adjust and hold the latter against casual rotation; the said adjustable means including a flanged and apertured sleeve in the frame, a threaded and apertured pin in the sleeve, and a nut on said pin. 50

3. A device or instrument for the purpose described, comprising a frame, a resilient 55 bendable element of uniform cross section throughout its length, adjustable means on the frame for holding said element against lengthwise movement, and element bending means carried by the frame and including a 60 worm gear, means for fastening the bendable element to the worm gear, housing means on the frame, and a worm meshed with said worm gear and disposed in said housing 65 means.

In testimony whereof I affix my signature.

NORMAN E. KLEIN.
